UNITED STATES PATENT OFFICE.

RICHARD GOBER, OF ALAMEDA, CALIFORNIA.

TOY.

1,209,143.

Specification of Letters Patent.

Patented Dec. 19, 1916.

Application filed February 7, 1916. Serial No. 76,877.

To all whom it may concern:

Be it known that I, RICHARD GOBER, a citizen of the United States, residing at Alameda, in the county of Alameda and State of California, have invented certain new and useful Improvements in Toys, of which the following is a specification:

This invention relates to improvements in toys and more particularly to a toy embodying the principle of a parachute.

The principal object of my invention is to provide an improved construction to be used in connection with a parachute whereby the device may be hurled a long distance into the air without opening, but when the same begins to fall will immediately open itself and so sail slowly to earth.

Another object of my invention is to provide a simple, strong and lightweight parachute element, which is reinforced in such a manner that tearing is to a great extent prevented.

Another object of the invention is to provide the weight element with a cushioning means in order to prevent injury in case same should strike a person or fragile object.

Still another object of the invention is to provide means whereby when the device is on its upward flight the parachute portion is held with its center in the direction of travel, and to provide spring means whereby when the weight element ceases to lift the parachute it is uncoupled therefrom allowing the parachute to reverse its position and open out in its downward flight.

With these and other objects in view my invention consists in the novel construction, combination and arrangement of parts hereinafter illustrated and more specifically pointed out in the appended claims.

Reference being had to the accompanying drawing forming a part of this specification, Figure 1 is a view in side elevation showing my improved toy as the same is arranged for throwing it upwardly. Fig. 2 is a view in side elevation showing the toy and parts positioned as in its downward flight. Fig. 3 is a view in section through the central portion of the parachute showing the latching device by which the parachute is prevented from opening in its upward flight. Fig. 4 is an enlarged sectional view through the weight used in the device. Fig. 5 is a view in front elevation taken at right angles to the plane of section showing in Fig. 2. Fig.

6 is a part section through the parachute element.

Referring to corresponding parts in the several views by the same numerals of reference, the device consists of the parachute element 1, which is constructed of the sector shaped pieces 2, reinforced along their adjoining edges by being overlapped and having the cords 3 inserted between these overlapping edges.

The edges are fastened by means of an adhesive or by stitching, and by this construction the fabric, generally paper, forming the sectors is not called upon to withstand strains which would quickly rupture the same. The inner ends of cords 3 are brought together at a point adjacent the apex of the sectors where a reinforcing patch of woven fabric 4 is attached, thus providing a strong light parachute element.

In the center of the reinforcing patch 4 on the inside thereof, is provided a metallic button 5, having the inwardly curved edges 6 forming an annular recess on the inside thereof. The fabric 4 is pressed into this recess and is held therein by means of the circular spring member 7, one end of which is bent to form the upright arm 8, which is curved outwardly over the center of the button, as shown at 9. Denoted by 10, is a spring member, the lower coil of which is seated within button 5 by being sprung into position in the same manner as ring 7. This spring is provided with an upwardly extending portion 11, having a loop adapted to embrace the curved end 9, the end 12 of the latter being bent upwardly so as to prevent the end of the spring member from overrunning the end thereof.

The lower ends of several of the cords 3 are brought together, knotted into a single strand as shown at 13, which in turn is fastened to a ring 14, and then to a common point 15. To the latter is attached a single cord 16, on the bottom of which is a weight 17. This weight comprises a member 18 of metal or other heavy material surrounded by the ball 19 of rubber or similar material. The latter is provided with an opening 20, through which the ball 18 is placed and from this opening is a hole 21 through which the cords 16 may extend. The opening 20 is somewhat smaller than the cavity in the center whereby the ball 18 is retained within the cover 19.

To use this toy the parachute 1 is folded

and the ring 14 is brought around to the top of the parachute and hooked over the end 9 of arm 8, pressing backwardly the spring arm 11. The parachute is then grasped by 5 its lower end and swung in a circle, whereby the weight elements 17 obtain considerable centrifugal force, so that when the parachute is released it will be propelled to a considerable height.

10 It will be apparent that the weight element offers less resistance to the air than the parachute, consequently, will exert an upward pull on the member 8, thereby holding the ring seated within the curved part 15 thereof. As soon, however, as the ball reaches the height where it no longer exerts a pulling action on the ring the spring arm 11 has sufficient tension to push the ring off of the hook, thereby allowing the parachute 20 to assume its proper position for opening, which it quickly does, and slowly floats to the ground.

It will thus be apparent that I have provided a novel toy, and while I have shown 25 the preferred embodiment of my invention it will be understood that changes may be made in minor details and construction without departing from the scope of the claims.

30 I claim as new and wish to cover by Letters Patent:

1. A toy comprising a parachute, a ring, cords extending from the outer edge of said 35 parachute to said ring, a weight attached to said ring, a curved arm attached to the center of said parachute on which said ring is adapted to be held and spring means for releasing said ring.

2. A toy comprising a parachute composed of sector shaped pieces, reinforcing

45 cords inserted in the seams between said pieces, a ring held by the outer ends of said cords, a weight secured to said ring, a curved arm attached to the center of said 50 parachute on which said ring is adapted to be held, and spring means for releasing said ring from said arms.

3. A toy comprising a parachute, a ring, cords extending from the outer edge of said 55 parachute to said ring, a weight attached to said ring, a cushion surrounding said weight, a curved arm attached to the center of said 60 parachute on which said ring is adapted to be held and spring means for releasing said ring.

4. A toy comprising a parachute composed of sector shaped pieces, reinforcing 65 cords inserted in the seams between said pieces, a ring held by the outer ends of said cords, a weight secured to said ring, a circular fabric reinforcement secured to the inner 70 ends of said sector shaped pieces, a concave button having an annular recess on the inside of said reinforcement, a circular spring ring on the outside of said fabric adapted to hold the said button in position, an upright arm formed on said ring over which 75 said ring is adapted to be hooked and spring means adapted to release said hook from said arm.

5. A toy comprising a parachute element, a weight, cords connecting said weight to said 75 parachute, a ring secured between said weight and said parachute, an arm secured to the center of said parachute, means for securing said arm to said ring and spring means for releasing said ring from said arm.

In testimony whereof I affix my signature.

RICHARD GOBER.
